UNITED STATES PATENT OFFICE.

BENJAMIN M. ROLPH, OF DIXON, ILLINOIS.

DITCHING-MACHINE.

1,241,661.

Specification of Letters Patent.

Patented Oct. 2, 1917.

Application filed December 26, 1914. Serial No. 878,999.

To all whom it may concern:

Be it known that I, BENJAMIN M. ROLPH, a citizen of the United States, residing at Dixon, in the county of Lee and State of Illinois, have invented certain new and useful Improvements in Ditching-Machines, of which the following is a specification.

My invention has reference to ditching machines, and more specially to that class of such machines which are used for forming trenches for the laying of tile and kindred purposes. My device is so constructed as to deliver the earth which is removed from the ground on both sides of the excavating wheel, and the excavating devices are secured in such a manner as to be readily removable, and capable of being replaced by others of different widths, so as to cut trenches of varying widths. The principal improvements comprise the parts by which this is accomplished, and these and other features of the device will more fully appear from the following specification, reference being had to the drawings accompanying the same, in which—

Figure 1 is a side elevation of my invention, with the cutting wheel in operating position. Fig. 2 is a similar view of the opposite side of the wheel. Fig. 3 is a front elevation of the forward supporting mechanism. Fig. 4 is a plan view thereof. Fig. 5 is a detail of the central part of such mechanism. Fig. 6 is a transverse section, medially of the machine, looking toward the forward end thereof. Fig. 7 is a detail, showing one of the scrapers 76. Fig. 8 is a cross-section on the line $\alpha-\alpha$ of Fig. 7. Fig. 9 shows one of the scoops in side elevation. Fig. 10 is a lower plan view thereof. Fig. 11 is an end view of the cutting end thereof. Fig. 12 is a detail of the roller 67 and drive mechanism therefor.

Similar parts are indicated by like letters of reference throughout the several figures. 45 1 represents the frame of the machine, preferably formed of angle-plate, supported by carrying-wheels 2, and provided with a tongue 3. At the rear end is mounted a

motor of any suitable design, as indicated at 4, by which is driven a shaft 5, on which 50 is fixed a sprocket-wheel 6, from which movement is imparted through a sprocket-chain 7 to a wheel 8 on a shaft 9 mounted on the frame. Fixed to the shaft 9 on the right hand side of the machine is a sprocket-wheel 10, (Fig. 2.) connected by a chain 11 with a sprocket-wheel 12 on a shaft 13 rotatably mounted on the frame 1. On the shaft 13 is also fixed a sprocket-wheel 14, connected by a sprocket-chain 15 with a 60 sprocket-wheel 16 secured on a shaft 17 rotatably mounted at the forward end of the machine. On the shaft 17 is fixed a drum 18, adapted to receive a cable 19 when the drum is properly rotated. The outer end 65 of the cable is secured to a fixed object ahead of the machine, or may be passed around such object and back to the forward end of the tongue 3, in a manner not shown in the drawings. Upon the cable being 70 wound upon the drum, by the operation of the motor, the machine is drawn gradually forward.

The manner of supporting the forward end of the frame 1 is preferably as shown 75 in Figs. 3, 4 and 5, in which 20 is a cross-piece secured at its ends to the side pieces of the frame 1, centrally of which cross-piece is rigidly secured a yoke 21 in the lower part of which a cross-beam 22 is supported on a pivot 23. At the ends of the beam 22 are fixed brackets 24 in which are held pivots 25 upon which the wheels 2 are mounted. Projecting forwardly from the pivots 25 are arms 27, united by a bar 28, 80 connected at a central point with the tongue 3. The rear end of said tongue is pivotally connected with the upper part of the yoke 21 by a brace 29, and with the lower part of the cross-beam 22 by a brace 30. When it is 85 desired to cause the machine to describe a curve the tongue is forced to one side or the other, as shown in broken lines in Fig. 4, resulting in the turning of the wheels in the same direction. In the use of the cable 19 95 this would be accomplished by establishing

the fixed point for the cable at one side or other of the direct line of travel of the machine. Secured from the ends of the cross-piece 20, so as to loosely embrace the cross-beam 22 at its ends, are guides 31, which permit a limited vertical movement of such ends. When the machine is passing over uneven ground the wheels are thus permitted to rise or fall without disturbing the 10 position of the frame or mechanism carried thereon.

Mounted on the sides of the frame 1 is an arch 32, within which is a frame 33 pivoted by means of arms 34 on the shaft 9. Secured to the upper part of the frame 33 are cables 35 which pass over pulleys 36 on the arch 32 and downwardly to a shaft 37 mounted on supports 37^a on the frame of the machine. On the shaft 37 is secured 20 a worm-gear 38, actuated by means of a worm 39 by means of a hand-wheel 40. By winding the cables 35 upon the shaft 37 the frame 33 is raised, and by a contrary operation it is lowered, for the purposes hereinintended set forth.

Rotatably supported by the frame 33 is a hub 41, forming the axis of a rim 42, attached thereto by means of spokes 43. Within the rim 42 is an internal gear 44, actuated by a gear-wheel 45 on the inner end of a shaft 46 mounted in a frame 47 secured to the frame 33. On the outer end of the shaft 46 is a sprocket-wheel 48, connected by a chain 49 with a wheel 50, fixed 30 on a shaft 51 supported on one side of the frame 33. The shaft 51 is operated from the shaft 9, in such manner that the parts just referred to, including the wheel 42, will be continuously in operation while the 40 machine is in movement.

Mounted on the rim 42 are pairs of standards 52 and 53, to each pair of which is attached a scoop 54, formed of a cutter 55, curved end-piece 56, and bars 57 uniting the 45 same. The scoops are removably secured to the standards by means of connections 58 and 59, held in place by means of bolts 60 and 61. Each of the scoops is also provided with a nose or point 62, removably secured 50 at the forward end of the cutter 55. The scoops are preferably of a shallow dish-shaped form, instead of semi-circular, so that there is not so great a tendency for a scoop-full of earth to be retained thereby. 55 The open character of the body of the scoop also facilitates the discharge of the contents thereof, especially in the case of wet and sticky dirt or clay, which would be inclined to adhere to the walls of a solid scoop. The supports 53 are shorter than the ones 52, so that each of the scoops has a gradual inclination with reference to the rim 42, toward the rear end of the scoops. This results in the earth being first en-

gaged by the point 62 of the scoop, which tears a small furrow therein, and then by the cutter 55, the beveled edges of which complete the cutting operation, the loosened earth being forced rearwardly into the scoop, where it is carried up to the 70 upper side of the wheel and discharged. To aid in holding the load of earth in the scoop until it reaches the point of discharge a gate 63 is pivoted to a projection 53^a by means of a shank 63^a, and held in position 75 normally by means of a stiff coiled spring 64 secured at one end to the projection 53^a and encircling the shank 63^a. The ordinary pressure of the earth in the scoop will be resisted by said gate, but in case of a 80 small obstacle being encountered, with a tendency to pass through the scoop, the gate will bend rearwardly sufficiently to permit the escape thereof.

The forward support 52 and connection 85 58 assist in loosening up the earth after an opening has been made therein by the point 62, but in order that said parts may work effectively it is necessary that they be located midway such point and the rear edges 90 of the cutter 55. In case said connecting parts are situated in a more rearward position, between the rear edges of the cutter, there is danger of the earth becoming clogged or jammed between such parts, interfering with the perfect action thereof. 95 If it is desired to excavate a trench of increased or decreased width this can be accomplished by removing the scoops 54 and replacing the same with others of greater 100 or less width.

Outside of the rim 42 are secured inclined shields 65 and 66, by which the earth, which is discharged from the scoops at the upper side of the wheel 42 is directed 105 outwardly upon rollers 67 and 68 supported from the frame 33, at each side of said wheel. The roller 67 is operated from a shaft 69, mounted on a part of the frame 33, on which shaft is secured a gear-wheel 110 70, engaging a similar wheel 71 fixed on the shaft 72 of the roller 67. (Fig. 12.) On the outer end of the shaft 69 is a sprocket-wheel 73 connected by a chain 74 (Fig. 1) with a similar wheel 75 on the 115 shaft 9. Movement is thus imparted to the roller 67 to suitably actuate the same during the forward movement of the machine. The roller 68 is similarly operated from the shaft 51.

To prevent the earth which falls from the scoops from falling back into the trench there is provided at each side of the machine a scraper 76, provided at its forward end with a rod 77 supported on a roller 78 125 held in a bracket 79 fixed to the cross-beam 22. The rod 77 is fixed to the scraper 76 by means of a yoke 80, (Fig. 8,) the ends of

which engage any pair of holes 81 in the end of said scraper. The height of the forward end thereof is thus capable of being adjusted, to give the desired inclination to 5 the scraper. The rear end of the scraper is supported from the frame 1 by a crank-arm 82, upon the upper end of which is fixed a collar 83, having a bearing on a bracket 84 fixed to the frame. This support, with the 10 roller bearing support at the forward end of the scraper, permits a limited longitudinal movement thereof. A rod 85 is connected at one end to an eye 86 fixed to the upper edge of the scraper and at the other 15 end to the lower part of the frame 33, near the hub 41. When the frame 33 is raised or lowered, carrying with it the ditching-wheel, the hub of such wheel describes the arc of a circle, and the rod 85 20 controls the longitudinal movement of the scraper 76, so that when such hub moves rearwardly the scraper moves rearwardly therewith, and similarly on the return movement. The forward end of the scraper is 25 also provided with means for adjustment of the degree of slant thereof with reference to the ground, such means comprising an arm 87 secured to the upper edge of the scraper, and a plate 88 having a series of 30 notches 89 adapted to be engaged by a bolt 90 held in a swivel-block 91 supported on a bracket 92 fixed to the cross beam 22. By moving the plate 88 inwardly or outwardly 35 the scraper 76 is rocked upon the rod 77, the upper edge of the scraper being thereby forced toward the frame 1 or away from it, and the lower edge of the scraper moved in a contrary direction. After the desired adjustment is secured the plate 88 is locked 40 in position by the bolt 90. The swivel mounting of the plate 88 permits it to conform to the longitudinal movement of the scraper.

At the sides of the frame 33 are pivotally 45 mounted small frames 93, to each of which is secured a scraper 94, capable of separating the earth from the scoops 54 as they reach the upper part of their movement. On account of the gradual inclination of the 50 scoops toward the cutting wheel, as hereinbefore mentioned, it is necessary to provide some method of drawing the scrapers 94 inwardly as they pass through the scoops, and prevent friction of such parts. This is accomplished in the following manner:—Attached to each of the frames 93 is a rod 95, extending downwardly and connected at its lower end with a trip-lever 96, (shown partly in broken lines in Fig. 1) which lever 55 is pivoted at its upper end to the frame 33, and is adapted to be engaged at its free end by a series of pins or rollers 97 carried by a disk 98 on the hub 41. In the rotation 60 of the cutting-wheel each of the pins 97 suc-

cessively comes in contact with the free end 65 of the lever 96, drawing the same downwardly and causing a downward movement of the frame 93 and scraper 94. The pins 97 are equal in number to the scoops 54 and are so disposed upon the disk 98 that one 70 of said pins engages the lever 96 as the scraper enters the scoop. When the scraper is leaving the scoop at the other end the pin slips past the end of the lever 96, permitting the return movement of the scraper to its 75 outer position. This upward movement is enforced by means of springs 99 secured at their lower ends to the frames 93 and at their upper ends to supports 100 fixed to the frame 33. The mechanism for controlling 80 the action of said scrapers, as just herein set forth, is not new of itself.

In the forward movement of the machine the rotation of the wheel 42 causes a constant operation of the scoops, which successively carry a load of earth to the upper part of the wheel, and discharge it on both sides of the machine, whereupon it is forced a sufficient distance from the excavation to permit of the laying of the tile therein. The 90 depth of the cut is readily adjusted by raising or lowering the frame 33.

What I claim as my invention, and desire to secure by Letters Patent of the United States, is:

1. In a device of the class described, in combination with a ditching wheel rotatably mounted, a scoop having a substantially V-shaped cutting member, provided at its point with a detachable cutting point, and a pair 100 of standards connecting the opposite ends of said scoop with said wheel, the standard at the forward end of said scoop being attached to said cutting member midway the cutting point and base thereof. 105

2. In a ditching machine the combination of a portable frame; a frame pivotally supported in said main frame so as to be vertically movable therein; an excavating wheel rotatably mounted in said last named frame 110 and adapted to deliver the excavated material at each side thereof; a pair of scrapers secured to the sides of the main frame so as to be longitudinally movable, and operatively connected with said vertically movable frame, so as to be actuated by the movement thereof. 115

3. In a ditching machine, the combination of a portable frame; a frame vertically movable therein; an excavating wheel rotatably 120 mounted in said last named frame; a scraper secured to the side of the main frame so as to be longitudinally movable, and operatively connected with said vertically movable frame; and means for vertical adjustment of the forward end of said scraper. 125

4. In a ditching machine, the combination of a portable frame; a frame vertically mov-

able therein; an excavating wheel rotatably mounted in said last named frame; a scraper secured to the side of the main frame, so as to be longitudinally movable, and operatively connected with said vertically movable frame, so as to move therewith; means for vertical adjustment of the forward end of said scraper; and means for adjustment

of the incline thereof with reference to the ground.

10

In testimony whereof I affix my signature in presence of two witnesses.

BENJAMIN M. ROLPH.
